CLAIM

The ornamental design for a utility waistbelt, as shown and described.

DESCRIPTION

In FIGS. 1, 2, 5 and 6, the belt portion is shown broken away to indicate indeterminate length;

FIG. 1 is a front elevational view of the utility waistbelt showing our new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.
